UNITED STATES PATENT OFFICE.

GEORGE W. BOND, OF RAYNHAM, MASSACHUSETTS.

WIRE-NAIL-MAKING MACHINE.

SPECIFICATION forming part of Letters Patent No. 529,475, dated November 20, 1894.

Application filed March 8, 1894. Serial No. 502,895. (No model.)

To all whom it may concern:

Be it known that I, GEORGE W. BOND, a citizen of the United States, residing at Raynham, in the county of Bristol and State of Massachusetts, have invented certain new and useful Improvements in Wire-Nail-Making Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to nail machines, and its object is to produce rapidly and cheaply, double ended nails or dowels, such as are largely used for fastening together the parts of barrel heads, boxes, furniture, and the like. The machine which I have invented consists of a combination of feeding devices, cutters, and grippers, by means of which a wire is fed, cut off in proper lengths and pointed, and then upset at any desired place to form a head between the pointed ends. The moving parts are all actuated from a single driving shaft which carries suitable cams.

In the drawings, Figure 1 is a perspective view of the machine. Fig. 2 is a top plan view. Fig. 3 is a longitudinal section on line 3—3, Fig. 2. Fig. 4 is a cross section on lines 4—4, Fig. 2. Fig. 5 shows the swing guide for the wire. Fig. 6 shows one of the gripping dies. Fig. 7 is one of the cutters, and Fig. 8 shows a dowel or nail made by the machine.

The frame A supports suitable bearings B for the driving shaft C, which has fast and loose pulleys c c', and a flywheel c². At one end of the shaft is a crank disk D carrying a crank pin d, which is radially adjustable in a diametrical slot in the disk, by means of a screw d'. A pitman E is connected with the crank pin by a ball joint, the brasses e being adjustable for wear as usual. The lower end of the pitman connects by a similar ball joint with a rock arm f on a rock shaft F extending transversely across the machine, and journaled in bearings f'. Secured to this rock shaft is an upright feed arm G, at the upper end of which is a stationary jaw g having a shank fitting into a hole in the arm. Below this jaw is an inclined jaw g' hinged at its

lower end, and having its upper end pressed against the stationary jaw g by a flat spring g². The inclined jaw is hinged in a block G' 55 which is adjustably fastened to the arm G by a bolt g³ passing through a slot g⁴ in the arm. A screw g⁵ enables the block G' to be pushed up to press the jaw g' tightly against the jaw g.

In the arm G, in line with the stationary 60 jaw, is a hole g⁶ through which is passed the wire X, which is firmly nipped between the jaws. Bolted to one side of the arm G is a bracket G², on which are carried straightening wheels G³, and G⁴, and a wiping device, 65 such as the box G⁵ filled with oiled waste. The wire passes through these devices before reaching the feed jaws g g'. In line with these jaws is a detent clamp H, consisting of a stationary jaw h and a movable jaw h', 70 mounted on a short shaft which is journaled in the bearing B'. This jaw h' has a tail h² which rests against the periphery of a cam H' on the shaft C. At the proper times, the cam closes and opens the jaws h h'. Adjacent 75 to the clamp on each side, are guides I K, the latter being vertically adjustable in an arm k.

The foregoing devices serve to straighten, feed, and guide the wire to the nail forming dies, and to detain the wire from being pulled 80 back when the feeding arm is retracted to get a fresh hold. It now remains to describe the means by which the wire is cut off, pointed at each end, and upset to form the head. In brief these results are effected by four dies 85 and two cutters. The latter sever the wire and form the point at one cut. The dies grip the ends of the severed piece of wire, and one pair moves toward the other pair to upset the metal between them.

Rigidly mounted on, or formed integral with the frame A is the die socket L in which are held by set screws one or more gripper dies M. These are preferably steel bars, having in their working ends grooves m to receive the 95 wire X and preferably roughened to give them a firm hold. In each of the other three die sockets L', L², L³, are one or more of these dies M, and they are all set at an acute angle, preferably forty-five degrees, with the line of the 100 wire X, the apex of the angle between the dies in each pair of sockets pointing in the direction said pair will move when forming the head upon the nail. I find it essential to

the operation of my machine that the dies be set at an acute angle to the wire, as described above, and as shown in the drawings.

In the sockets $L^2 L^3$ are cutters N, arranged 5 behind the gripper dies M. Each cutter has two cutting edges n crossing each other, so that when the two cutters are forced against the opposite sides of the wire, it will be severed, and the cut ends of the wire will be 10 beveled to a point, as shown in Fig. 8. The dies and cutters all lie in the same horizontal plane. As stated above the socket L is stationary. The other sockets are movable, sockets $L' L^2$ having motion transverse to the 15 wire in order to co-operate with sockets $L L^3$ respectively in gripping it; while sockets $L^2 L^3$ have a movement lengthwise of the wire to effect the formation of the head upon the nail. Socket L^2 , therefore, has both motions. 20 The construction which permits and accomplishes these movements is as follows: Socket L' is mounted upon or forms a part of a lever l' fastened to or integral with a longitudinal rock shaft O journaled on conical bearing 25 pins P. Socket L^3 is similarly mounted upon a transverse rock shaft O' supported upon pins P'. The lever l' carrying socket L^2 is fast 30 on a transverse rock shaft O' supported on pins P' which are carried in a yoke O³, journaled 35 on a longitudinal axis on pins P³. This mounting of the socket L^2 constitutes a universal joint which permits it to be moved both lengthwise of and transverse to the wire. The conical pins are all adjustable for wear 40 by means of plates Q and screws q, which also permit the pins to be readily removed.

The sockets $L' L^2$ are simultaneously rocked on their pins P P' by a cam R on the shaft C, which bears against the upper part of the 45 levers l' l². The lengthwise movement of the socket $L^2 L^3$ is produced by the transverse cam shaft S which has a hardened plate s bearing against the levers carrying the sockets. The cam shaft is actuated by an arm s' connected 50 by a ball bearing with the pitman S' which has at its upper end a yoke encircling a cam or eccentric R' on the shaft C. Attached to each socket is a retracting spring, to insure the opening of the dies after the nail has been 55 made. These springs may be of any suitable construction, and may be omitted when the machine is run at low speed. In the drawings I have shown one form of spring, being a bent steel bar T rigidly held at one end in a block t, and having its free end connected by a rod t' with the socket.

A cross bar U is held by adjusting screws u in standards B² on the frame A, and limits 60 the backward movement of the sockets $L^2 L^3$ after the head is formed. The amount of this movement determines the amount of material used to form the head. A movable or swing guide for the wire is supported by this cross bar, and serves to carry the wire out of the 65 cutter in the socket L^3 , so as to insure its being free to be fed forward for the next nail. This guide V depends from a block v in a lug

w rising from a plate W which is secured by bolts u' to the cross bar U, said bolts passing through slots w' to render the plate longitudinally adjustable. The guide V is thus capable of swinging transversely to the path of the wire, and toward and away from the socket L^3 . A bar Y in the socket L^2 operates to push the guide toward the socket L^3 when 70 the sockets $L^2 L^3$ come together. When they separate, the guide is swung away from the socket L^3 by means of a coiled spring v² acting against an arm on the block v. A screw v³ serves as a stop to regulate the normal position of the guide. 80

A clearer Z, consisting of a thin blade adjustably secured to a stationary arm z, projects between the sockets $L' L^2$ and serves to push the formed nail out of the dies when the 85 sockets separate. The arm z is bolted to one of the standards B² supporting the cross bar U.

A screw b, carried by the framework contacts with a lug l on the socket L' and sustains it against lengthwise pressure when the 90 nail is formed, thus relieving the pins P from all undue strain.

The operation of my machine is as follows: The wire is nipped by the feed jaws g g' and the forward movement of the feed arm pushes 95 it through the guides, the detent clamp being open, until the end of the wire lies between the dies, which now stand retracted. The detent clamp then seizes the wire, and the feed arm moves back for another hold, 100 carrying with it the straightener and oiler which thus operate on a fresh length of wire. The range of movement of the feed arm and consequently the length of the nail, is regulated by the radially adjustable crank 105 pin d. As soon as the wire has been fed, the socket L' moves toward the socket L and likewise the socket L^2 moves toward the socket L^3 , the dies in each pair gripping the wire firmly, and the cutters in the last named pair 110 severing and pointing the wire. (See Fig. 3.) The sockets $L^2 L^3$ then move simultaneously toward the other pair, thereby upsetting a head on the piece of wire between them, which is firmly held by the dies and the cutters. The 115 sockets then separate, and release the nail, any tendency to stick in the dies being prevented by the clearer Z. At the same time, the swing guide frees the end of the wire from the cutters, and holds it in a position to be fed 120 forward by the next stroke of the feed arm.

Having thus described my invention, what I claim is—

1. A nail making machine, comprising a wire-feeding device, a detent clamp, two pairs 125 of gripping dies, a pair of cutters adjacent to and moving with one pair of dies, and means for causing said latter pair of dies to approach the other pair, substantially as described.

2. In a wire nail-making machine, the combination with a stationary die, of a die movable transverse to the wire to co-act with the stationary die in gripping it, a third die movable both transverse and lengthwise of the

wire, and a fourth die movable lengthwise of the wire only, the third die co-acting with the fourth to grip the wire, and the two pairs of gripping dies co-acting to upset the wire between them, substantially as described.

3. In a wire nail-making machine, the combination with a pair of gripping dies set at an acute angle to the line of the wire, of a second pair of gripping dies and a pair of pointing cutters adjacent thereto, all set at an acute angle to the wire, the apex of the angle formed by one pair of dies pointing toward the apex of the angle formed by the other pair, substantially as described.

15 4. In a wire-nail-making machine, the combination with a stationary die-socket, of a die-socket lever fulcrumed on an axis parallel with the line of the wire, a die socket lever fulcrumed on an axis transverse to the line of the wire, a die-socket lever fulcrumed on a universal joint so as to have motion both transverse and lengthwise of the wire, and means for actuating these levers, substantially as described.

25 5. In a wire-nail-making machine, the combination with the stationary die-socket, of three movable die-sockets each mounted on a

lever, a driving shaft carrying cams for moving the first and second of said levers, and a cam shaft actuated from said driving shaft, 30 for moving the second and third of said levers, substantially as described.

6. The combination with the stationary die-socket L, of the movable sockets L', L², L³, the rock shafts O, O', O² supporting said sockets, the yoke O³ supporting the shaft O³, the driving shaft C carrying the cams R, R', the cam shaft S having a rock arm s', and the pitman S' connecting said arm with the cam R', substantially as described.

35 7. In a nail making machine, the combination with the cross bar U, of the plate W adjustably secured thereto, the block v journaled on the plate W, and provided with an arm, a coiled spring v² acting against said arm, and the guide V depending from said block, substantially as described.

In testimony whereof I affix my signature in presence of two witnesses.

GEORGE W. BOND.
